WEATHER STRIPPING

David Abernethy, Philadelphia, Pa.

Application January 6, 1934, Serial No. 705,483

3 Claims. (Cl. 20—69)

The object of my invention is to devise novel weather stripping which can be economically manufactured, which can be applied to the window frames by unskilled labor, and which will effectively seal the sash in the window frames to prevent the entrance of air, dirt, dust and foreign materials.

A further object of my invention is to devise a novel weather stripping adapted to be inserted between the bead or dividing strip and the wall of its slot to provide a spring flange forming an obtuse angle with the body portion of the weather stripping so that it will contact with a side rail of the sash.

15 A further object is to provide a novel weather stripping for the top and bottom of the window.

With the above and other objects in view as will hereinafter fully appear, my invention comprehends novel weather stripping.

20 It further comprehends novel weather stripping formed from spring sheet metal to provide a body flange preferably reinforced to fit between the bead and the wall of its slot, and a sealing flange presented at an obtuse angle to the body flange and reinforced if desired by creasing or bending or by a double fold.

25 It further comprehends novel weather stripping for the top and bottom of the windows.

Other novel features of construction and advantage will hereinafter clearly appear in the detailed description and the appended claims.

30 For the purpose of illustrating the invention, I have shown in the accompanying drawing typical embodiments of it, which, in practice, 35 will give satisfactory and reliable results. It is, however, to be understood that the various instrumentalities of which my invention consists can be variously arranged and organized, and my invention is not limited to the exact arrangement and organization of these instrumentalities as herein set forth.

35 Figure 1 is a perspective view of a window frame and its sash partly broken away, and illustrating in assembled position, weather stripping embodying my invention.

40 Figure 2 is a transverse section with the sash removed.

45 Figure 3 is a perspective view of a strip of weather stripping embodying my invention.

50 Figure 4 is a transverse section of a portion of a window with the sash in place.

55 Figure 5 is a perspective view of a portion of a sash with weather stripping embodying my invention.

Figure 6 is a sectional elevation of the construction shown in Figure 5.

Figure 7 is a perspective view of another form of weather stripping embodying my invention.

Figure 8 is a perspective view of another form of weather stripping embodying my invention.

Figure 9 is a perspective view of another form of weather stripping embodying my invention.

Figure 10 is a detail showing a separator employed between the flanges 7 and 8.

Figure 11 is a perspective view of another embodiment of my invention.

Similar numerals indicate corresponding parts.

Referring to the drawing:

15 1 designates the window frame of conventional construction, having a slot 2 to receive the bead or dividing strip 3 for the top sash 4 and the bottom sash 5. 6 designates a strip of weather stripping embodying my invention, and formed from spring metal in sheet form.

20 The weather stripping has a rear flange 1 which merges into a front flange 8 folded over upon the rear flange and having a hinge portion 9. The front flange 8 merges into an angularly inclined spring flange 10 which forms with the flange 8 an obtuse angle and has a hinge portion 11.

25 The depth of the front flange 8 is not greater than the depth of the slot 2 and is preferably of less depth so that the hinge portion 11 will be in close proximity to the wall of the window frame against which the sash contacts.

30 The weather stripping is inserted between the separating bead 3 and the wall of the slot 2 so that the inner portion of the rear flange and the front flange will be fixed in position and the spring flange 10 will extend as shown in Figure 2. The strip of weather stripping preferably extends from the bottom of the frame above the top of the lower sash, and the other strip of weather stripping on the same side of the window frame extends from the upper portion of the window frame below the bottom of the lower sash when the latter is in its raised position.

35 45 I have shown the spring flange 10 of such width that it will clear the pulley for the sash cord, but it can be made wider if desired and cut away for clearance at the location of the pulley. The width of the rear flange may vary but it is preferably wider than the front flange.

50 55 When the sash is in place the front flange will be forced against the juxtaposed wall of the window frame and effectively seal the sash in the window frame.

If the opening between the bead and the wall of the slot is too wide for the weather stripping to closely fit therein a separator member 12 may be driven in between the front and rear flanges 5 to cause them to flare outwardly into engagement with the juxtaposed walls of the bead and window frame.

If desired the front flange may have its front marginal portion inwardly deflected as at 13, 10 Figure 8.

The front flange 10 may also be deflected rearwardly upon itself as at 14, Figure 9, the hinge for such flange being at 15. This reinforces the flange 10 so that the flanges 10 and 14 will be 15 in close engagement with the juxtaposed walls of the sash and window frame.

In some cases the rear flange may be omitted as shown in Figure 7, in which case the body flange 16 is insertable alongside of the bead 20 and the spring flange 17 extends outwardly 20 therefrom to form an obtuse angle.

The top of the upper sash and the bottom of the lower sash is sealed by a different form of weather stripping and I preferably employ the 25 construction seen in Figures 5 and 6, wherein the strip has a flat body portion 18 secured by fastening devices 19 to the sash, and provided with a preferably deflected hinge portion 20 which merges into the outwardly flared spring flange 21. 30 The edge of the sash rail is bevelled off as at 22 to receive the hinge 20, if the latter is offset.

The weather stripping can be economically 35 formed from spring metal in sheet form.

If after being in use for a long time the spring 35 flange becomes more or less set, it can be flared outwardly by drawing a screw driver, knife or other tool along its inner wall.

When the weather stripping is to be applied 40 to window frames already installed and in use and the bead 3 closely engages the wall of the slot 2, a knife or other tool can be used along the bead to provide sufficient clearance for the insertion of the flanges 7 and 8 of the weather stripping.

45 The flanges 7 and 8 form an angularly shaped seal for the space between the side of the sash and the window frame and between the window frame and the bead.

In the embodiment seen in Figure 11, the 50 strip is folded upon itself to form a body flange 24 a front flange 25 and a laterally extending flange 26 which terminates in an inwardly offset rounded hinge portion 27, adapted to seat in a groove 28, in the window frame, and connected with an inwardly deflected spring flange 29. The flange 26 is substantially at a right 55 angle to the flange 25 so that it will closely engage the adjacent wall of the window frame.

The construction shown in Figure 11 is similar 60 to that shown in Figure 9 except that the hinge portion is not offset. If the hinge portion is not offset, it is not necessary to employ the groove 28, as is apparent.

If after a long period of use the spring flanges 65 such as 15 or 29 become more or less set, they can be bent outwardly to their original position by running a suitable tool between them and the juxtaposed laterally extending flange such as 10 or 26.

70 The embodiments seen in Figures 9 and 11 provide a very effective seal since it may be securely wedged alongside of the dividing strip or bead, with the flange 10 or 26 engaging the window frame, and with the spring flange pressing 75 against the sash.

In all of the embodiments of my invention as herein shown, I provide a spring flange which exerts a continuous spring pressure to form an effective seal. The hinge may be flat but it is preferably rounded to render it more durable. 5

The weather-stripping at its ends may be tacked to the window frame if desired although this is not necessary as it has a friction fit between the bead and the sash.

It will now be apparent that I have devised 10 a new and useful weather-stripping, which embodies the features of advantage enumerated as desirable in the statement of the invention and the above description, and while I have, in the present instance, shown and described preferred 15 embodiments thereof which will give in practice satisfactory and reliable results, it is to be understood that these embodiments are susceptible of modification in various particulars without departing from the spirit or scope 20 of the invention or sacrificing any of its advantages.

Having thus described my invention, what I claim as new and desire to secure by Letters Patent is:—

1. The combination with a window frame, having a slot with a bead in the slot, and the window sash, of a weather strip of spring material comprising a rear flat flange merging into a flat front flange deflected over it, with said flanges inserted between the bead and a side wall of the slot, said front and rear flanges being bendable to seal the space between the bead and the juxtaposed wall of its slot, said front flange merging into an outwardly extending 30 flange at right angles to it and contacting with the window frame to effect a seal with a wall of the window frame, said rear flange effecting a seal with the window sash, said right angle flange merging into an inwardly extending 40 spring flange disposed at an angle to it and bearing against the outer wall of the sash.

2. The combination with a window frame, having a groove, a slot with a bead in the slot, and the window sash, of a weather strip of 45 spring material comprising a rear flat flange merging into a flat front flange deflected over it and contacting with it throughout its area, with said flanges inserted between the bead and a side wall of the slot, said rear flange extending to overlie the window sash, said front flange merging into an outwardly extending flange at right angles to it and contacting with the window frame, said right angle flange merging by an offset hinge portion into an inwardly 55 extending spring flange disposed at an angle to it and bearing against the outer wall of the sash, said offset hinge portion being received in said groove.

3. The combination with a window frame, having a slot with a bead in the slot, and the window sash, of a weather strip of spring metal comprising a rear flat flange merging into a flat front flange deflected over it, with said 65 flanges inserted between the bead and a side wall of said slot, said front flange merging into an outwardly extending flange at right angles to it and contacting with the window frame, said right angle flange merging by an offset hinge portion with an inwardly extending spring flange disposed at an angle to the right angle flange, said spring flange bearing against the outer wall of the sash. 70
